UNITED STATES PATENT OFFICE.

EMIL A. PETERSON AND WILLIAM J. MCGINNIS, OF APPLETON, WISCONSIN.

HYDRAULIC CONTROL ATTACHMENT FOR BEATING, BLEACHING, AND WASHING ENGINES.

1,416,056.

Specification of Letters Patent. Patented May 16, 1922.

Application filed January 26, 1920. Serial No. 354,155.

To all whom it may concern:

Be it known that we, EMIL A. PETERSON and WILLIAM J. MCGINNIS, citizens of the United States, and residents of Appleton, in the county of Outagamie and State of Wisconsin, have invented new and useful Improvements in Hydraulic Control Attachments for Beating, Bleaching, and Washing Engines, of which the following is a description, reference being had to the accompanying drawings, which are a part of this specification.

The present invention relates to certain new and useful improvements in hydraulic control attachments for beating and washing machines and refers more particularly to beating, bleaching and washing engines especially adapted for use in preparing stock in the manufacture of paper.

20 The present devices now on the market for adjusting the beating roll and the washer employ a jack screw which has proven very unsatisfactory in that the movement of the roll and washer from one position to the other is "jerky" and further that such a device lacks the flexibility required in a device of this character.

With these inherent objections in mind, our invention has for one of its objects to 30 provide hydraulic means for vertically adjusting the beating roll and washer of a paper pulp preparing machine which will have the desired flexibility and which will be capable of fine adjustment.

35 Another object of the present invention is to provide hydraulic adjusting means for a beating roll which will have means for automatically permitting the pressure to escape therefrom as the stock becomes finer, and 40 thus effect the automatic adjustment of the beating rolls.

A further object of the present invention is to provide hydraulic adjusting means for the beating roll and the washer of a paper 45 stock comminuting machine which will have means for controlling the limit of movement of said beating roll and said washer in both directions.

50 A still further object of the present invention is to provide a combined supporting standard and hydraulic cylinder for engaging one end of a lever journally supporting the beating roll and having its other end fulcrumed to another supporting standard.

With the above and other objects in view 55 which will appear as the description proceeds, our invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, we have 65 illustrated one complete example of the physical embodiment of our invention, constructed according to the best mode we have so far devised for the practical application of the principles thereof, and in which:

70 Fig. 1 is a side view of a portion of a paper stock beating and washing machine equipped with our invention, parts being broken away and in section to more clearly illustrate the details of construction.

75 Fig. 2 is a top plan view thereof, parts being broken away and in section to illustrate various structural details.

80 Fig. 3 is a sectional view through one portion of the machine on the line 3—3 of Fig. 2, parts of the hydraulic cylinder and the yoke member connected with the washer being broken away and in section.

85 Fig. 4 is a diagrammatic view, part in section and part in elevation illustrating the hydraulic rams for operating the beating roll and the washer and their various pipe connections, and

90 Figure 5 is a view part in section and part in elevation taken through the relief valve for governing the descent of the roll.

95 Referring now more particularly to the accompanying drawings, 5 designates a paper stock beating and washing machine container having disposed therein a central wall or partition 6, spaced from the ends of the container and dividing the same into two communicating sections; 7, a beating roll or rotor disposed in one of the sections and having its supporting shaft 8 journalled in bearings 9 secured to levers 10 (to be later described) medially of their ends; and 11, a washer disposed in the other section of the container and mounted upon a supporting shaft 12 journalled in bearings 13 as later 100 described.

105 The beating roll or rotor 7 is rotated by means of a drive pulley 14 mounted on its

shaft 8 and connected by any suitable means to a source of power, not shown. The washer 11 is connected with the driven shaft 8 by means of suitable belt connections 15 5 and gears 16 as best shown in Fig. 2. The operation of the beating roll 7 and the washer 11 is briefly as follows:

The stock is placed within the container 5 together with water at a desired level and 10 the rotation of the beating roll and the washer causes the stock to pass through the two sections of the container. The roll 7 coats with a bed plate 7', including bed knives and bed knife receptacles, to comminute the stock as it passes therebetween, the stock being forced up and over a back-fall 17 and then travels around through the container, the water being cleansed from the impurities which float upon the top by means 20 of the washer 11 which revolves in an opposite direction to the material. As the stock becomes finer, the roll 7 is lowered to decrease the space between it and the bed plate 7' until the stock is thoroughly comminuted.

25 All of the foregoing mentioned operation is well known in the art, and our invention resides in the novel means employed for raising and lowering the beating roll or rotor 7 and in adjusting the washer 11 as herein-after described.

Disposed adjacent each side of the container 5 is a pair of vertical supporting standards 18 and 19 with which the levers 10 are connected. The standards 18 and 19 35 have their lower ends reinforced or enlarged as at 20 and the adjacent standards 18 and 19 are connected together at their lower portions by means of a skeleton brace construction 21 as best shown in Fig. 1. Each lever 40 10 has one end extended into its adjacent standard 18 through a slot or groove 22 and pivotally secured therein, as at 23, and its other end projected into the adjacent standard 19 through a slot or groove 24 and is 45 connected, by means to be later described, with a piston 25 slidably mounted within a cylinder 26 formed in the lower enlargement 20 of the standards 19. From this structure it will be obvious that the standards 18 function 50 as fulcrums for the levers 10.

The end of each lever 10 disposed within its adjacent standard 19 is formed with a vertical bore 27 which is flared upwardly and outwardly and has mounted therein the 55 upper end of a connecting rod 28 which is pivoted as at 29 to the piston 25. As best shown in Fig. 1, a shoulder 30 is formed on the rod 28 and impinges the under side of the lever 10 adjacent its bore 27 and has 60 secured to its upper end disposed above the top face of the lever 10 a pair of locking nuts 31. The flaring or tapering of the bore 27 and the pivotal connection 29 between the rod 28 and piston 25 permits the vertical 65 movement of the end of the lever 10 as will

be apparent, and to prevent the end of lever 10 disposed within the adjacent standard 19 from binding against the inner wall of the standard, the end of the lever is slightly curved as at 32.

70 Both cylinders 26 are coupled together by means of a pipe 33, the ends of which enter the cylinder as at 34, and communicating with the pipe 33 intermediate its ends 34 is a supply or intake pipe 35 connected with suitable means for supplying fluid under pressure and controlled by means of a valve 36, and also communicating with the pipe 33 intermediate its ends 34 is a drain pipe 37 having therein a control valve 38. To raise the roll 7, valve 38 is closed by movement of its handle 38', and the valve 36 opened by means of its handle 36' which allows fluid under pressure to pass from the pipe 35 through pipe 33 and into the 85 cylinders 26 where the fluid impinges against the pistons 25 and urges them upwardly, carrying with them the roll 7 by reason of their connections with the levers 10 as before described.

90 In order to check or limit the upward movement of the pistons 25 and the elements connected therewith to prevent damage or injury to the machinery, we provide a valve 39 in the pipe 35 intermediate valve 36 and pipe 33 which is normally held open by means of a lever 40 pivoted to the top of one of the standards 19 as at 41 and having one end connected to the valve 39 by means of a link 42 and its other end provided with a 100 counter-balance weight 43. The weight 43 normally urges the valve 39 to open position, and when the lever 10, adjacent the lever 40 reaches its upward limit of movement, it engages a depending arm 44 carried by the lever 40 and moves the same against the action of weight 43 closing the valve 39 and thus checking the upward movement of both pistons 25. As the drain valve 38 is closed, the pistons 25 will be retained in 110 their upward position as will be understood. When the upward movement of the pistons 25 is checked or stopped by the automatic device just described, the valve 36 is then closed so that the automatic lowering device 115 now about to be described may function properly.

120 Disposed within the pipeline 35 between valve 38 and pipe line 33 is an auxiliary relief line 37' having therein a spring actuated relief valve 45. The valve 45 is of any well-known construction and in the present embodiment, is illustrated as comprising a casing having an end 72 connectible with the relief line 37' and an end 73 connectible with the line 33 through the line 37. The casing has a partition 74 therein disconnecting ends 72 and 73 and having an opening therein normally closed by a valve 75 normally yielding urged to closed position by a 130

spring 76 confined between a web or partition 77 and a washer 78 secured in place by adjustable lock nuts 79 on the outer end of the stem 80 of said valve. The spring 76 is 5 of sufficient tension to normally maintain the valve 75 in closed position, but when the density of the material, which assists in supporting the beating roll, is decreased, the pressure in the line 33 increases to a point 10 sufficient to overcome spring 76 and communicate line 33 with relief line 37'.

In the operation of the machine, the roll 7 is dropped gradually as the stock becomes finer and the relief valve 45 automatically 15 effects this adjustment. The weight of the rotor or beating roll 7 is supported somewhat by the stock passing between it and the bed plate 7' and as the stock becomes finer the density of the material assisting in supporting the rotor or beating roll decreases 20 and consequently increases the pressure within the cylinders 26 and the pipe line 33. The relief valve 45 is adjusted so that as the pressure is increased as described, it will be operated to open the auxiliary drain line 37' 25 and allow the rotor or beating roll 7 to be dropped. When the rotor has dropped sufficiently to have a portion of its weight supported by the stock, the relief valve will automatically close. The downward limit of 30 movement of the rotor or beating roll 7 is governed by means of a jackscrew 46 carried by a socket or standard 47 formed on the braces 21 and engaging the ends of the levers 35 10 adjacent the standards 19.

The bearings 13 of the washer supporting shaft 12 are shaped to have sliding engagement with a pair of washer posts 48 secured to the partitions 6 and the adjacent outer 40 wall of the container. The washer posts have their upper ends connected by means of a transverse member 49 to thus provide a supporting and guiding frame for the washer 11. The bearings 13 are movable 45 along the washer posts and to move the same to effect the adjustment of the washer 11, we provide a pair of connecting rods 50 connected to the bearings as at 51 and having their upper ends passed through guide openings 52 formed in the upper ends of the washer posts 48 and connected as at 53 to the arms 54 of a yoke member 55.

The yoke 55 surrounds a vertical cylinder 56 which has its lower end secured to and 55 closed by transverse member 49 and its upper end provided with a cap 57 having therein a central bore through which passes a piston rod 58 having its lower end connected to a piston 59 mounted within the cylinder 60 and its upper end secured to the yoke 55 as at 60. The member 49 has a threaded opening therein communicating with the cylinder 56 in which is secured the end of a supply pipe 61 which is connected with suitable 65 means for supplying fluid under pressure

and has therein a control valve 62 having an operating handle 62'. Communicating with the supply pipe 61 intermediate the cylinder 56 and control valve 62 is a drain pipe line 63 having therein a control valve 64 having a 70 control handle 64'. To raise the washer 11 the valve 64 is closed and valve 62 opened allowing fluid under pressure to impinge against the piston 59 and raise the yoke 55 and consequently the washer 11 by means of 75 its connections therewith.

The upward movement of the washer 11 is controlled by a counter-balance lever 65 having one end connected to a normally opened valve 66 in the line 61 intermediate 80 valve 62 and the cylinder 56 by means of a link 67 and having its other end counterbalanced by a weight 68. The lever 65 is medially pivoted to one of the washer posts 48 and is engageable by the adjacent portion of shaft 12 when it reaches its upward limit of movement, thus overcoming weight 68 and moving the rod or link 67 downwardly to close the valve 66 and shut off the supply of fluid to the cylinder. 90

To lower the washer, the valve 62 is closed and valve 64 opened to allow the fluid from the cylinders to drain, and when the washer has reached the position desired, valve 64 is closed as will be obvious. The downward 95 movement of the washer 11 is limited by means of the arms 54 resting upon the transverse member 49. The usual drain for the washer 11 is provided as at 69 having a spout or outlet 70 telescoped within a bowl 100 71 adapted to be connected to an outlet pipe, not shown. The bowl 71 is secured to the adjacent side wall of the container 5 and serves as a support for the adjacent washer post 48. 105

From the foregoing description taken in connection with the accompanying drawings, it will be readily apparent to those skilled in the art to which an invention of this character appertains, that the adjustment 110 of the rotor or beating roll 7 and the washer 11 may be readily obtained and that the movements of the same will not in any manner interfere with their driving connections and that the adjustment may be made as 115 exact as may be desired.

What we claim as our invention is:

1. In a paper pulp machine, the combination with a bed plate and a beating roll coacting therewith to beat materials passing therebetween into a pulp, of means for raising said beating roll, and means for automatically lowering said roll as the density of the material being worked upon decreases. 120

2. In a paper pulp machine, the combination with a bed plate and a beating roll coacting therewith to beat materials passing therebetween into a pulp, of hydraulic means for spacing the beating roll from the bed plate, and means for automatically adjust- 125 130

- ing the space between said beating roll and bed plate as the density of the materials being worked upon decreases.
3. In a machine of the class described, the combination with a bed plate and a beating roll coacting therewith, of fluid actuated means for spacing the beating roll from the bed plate, means communicating said fluid actuated means with a source of fluid supply to raise the roll, and means operable to disconnect said source of fluid supply upon the upward movement of the roll a predetermined distance.
4. In a machine of the class described, the combination with a bed plate and a beating roll coacting therewith, of fluid actuated means for spacing the beating roll from the bed plate, means communicating said fluid actuated means with a source of fluid supply to raise the roll, means operable to cut off said source of fluid supply upon the roll reaching a predetermined height to limit its upward movement, and means independent of the fluid actuated means for limiting the downward movement of the roll.
5. In a paper pulp machine, the combination with a bed plate and a beating roll coacting therewith, of hydraulic means for spacing said beating roll from said bed plate, a control valve for operating the hydraulic means, and means connected with the control valve and operable upon a certain limit of movement of said beating roll to check the movement of said roll.
6. In a machine of the class described, the combination with a bed plate and a beating roll adjustably disposed thereover and coacting therewith to comminute stock passed between, of fluid actuated means for spacing the beating roll from the bed plate, a supply pipe for the fluid actuated means, the weight of said roll being supported partially by the stock passing between it and the bed plate and partially by said fluid actuated means, the pressure in said supply pipe being increased upon the density of the stock being decreased, and means operable upon the pressure in said supply line reaching a predetermined amount to lower said roll.
7. In a machine of the class described, fluid actuated adjusting means for a beating roll, comprising a roll carrying member, a fluid actuated ram connected with said member to raise and lower the same, and means for actuating said ram to adjust the roll upon a change in the body density of materials being worked upon by the roll.
8. In a machine of the class described, the combination with a bed plate and a beating roll adjustably disposed thereover and coacting therewith to comminute stock passed therebetween, of fluid actuated means for spacing the beating roll from the bed plate, a supply pipe for the fluid actuated means, a drain pipe for the fluid actuated means, the weight of said roll being partially supported by the stock passing between it and the bed plate, and a relief valve in the drain pipe for automatically lowering the beating roll when its weight is not partially supported by the stock due to a decrease in the density of the stock.
9. In a paper pulp machine, hydraulic adjusting means for a beating roll comprising a pair of standards, a lever having one end pivoted to one of the standards and its other end slidably mounted in the other standard, a cylinder formed in the lower portion of said other standard, a piston mounted in said cylinder and connected with the slidable end of the lever, means for supplying fluid under pressure to the cylinder to move the piston and with it said lever, and means engageable by the slidable end of said lever, when it has reached a certain limit of movement, for cutting off the supply of fluid to the cylinder.
10. In a machine of the class described, fluid actuated adjusting means for a beating roll, comprising a pair of levers journally supporting medially of their ends a beating roll supporting shaft, a pair of standards supporting each lever, each lever having one end in pivotal engagement with one standard and its other end slidably supported within another standard, fluid actuated means connected with the slidably supported end of each lever, means for connecting said fluid actuated means with a source of fluid supply to raise the beating roll, and means operable upon the slidably supported ends of the levers reaching a predetermined height to disconnect said source of fluid supply.
11. In a machine of the class described, the combination with a washer, of fluid actuated means for adjusting the washer, means for connecting said fluid actuated means with a source of fluid supply to adjust the washer, and means for disconnecting said fluid supply upon the washer reaching a predetermined position of adjustment.
12. In a paper pulp machine, the combination with a revoluble washer, of hydraulic means for vertically adjusting the revoluble washer, a control valve for operating the hydraulic means, and means connected with the control valve and operable upon a certain upward limit of movement of the revoluble washer to check the movement of the washer.
13. In a paper pulp machine, the combination with a washer, its supporting shaft and bearings, of a yoke member connected with the shaft bearings, and a hydraulic ram connected with the yoke member for raising and lowering the same.
14. In a paper pulp machine, the combination with a washer, its supporting shaft, and bearings therefor, of adjusting rods having their lower ends engaged with said bearings,

a yoke member carried by the upper ends of the adjusting rods, a hydraulic ram connected with the yoke member, and control means for moving said ram vertically to adjust the 5 washer.

15. In a paper pulp machine, the combination with a washer, its supporting shaft, and bearings therefor, of adjusting rods having their lower ends engaged with said bearings, 10 a yoke member carried by the upper ends of the adjusting rods, a hydraulic ram connected with the yoke member, means for moving the ram vertically, and means operable when the washer has reached a certain 15 limit of movement to check the movement of the ram.

16. In a paper pulp machine, a supporting frame including side washer posts and a transverse brace bar connecting the upper 20 ends of the washer posts, a cylinder centrally carried by the transverse brace bar of the supporting frame, a yoke member disposed adjacent the cylinder, a piston mounted in the cylinder and connected with 25 the yoke member, means connecting the yoke member with the supporting shaft of a washer, and means for controlling fluid under pressure within the cylinder to raise and lower the piston.

30 17. In a paper pulp machine, a supporting frame including side washer posts and a transverse brace bar connecting the upper ends of the washer posts, a cylinder centrally carried by the transverse brace bar of 35 the supporting frame, a yoke member disposed adjacent the cylinder, a piston mounted in the cylinder and connected with the yoke member, means connecting the yoke member with the supporting shaft of a 40 washer, an intake for the cylinder for supplying fluid thereto under pressure to raise

the piston, and a drain for the cylinder for releasing the pressure from the cylinder to lower the piston.

18. In a paper pulp machine, a supporting 45 frame including side washer posts and a transverse brace bar connecting the upper ends of the washer posts, a cylinder centrally carried by the transverse brace bar of the supporting frame, a yoke member disposed adjacent the cylinder, a piston mounted in the cylinder and connected with the yoke member, means connecting the yoke member with the supporting shaft of a washer, an intake for the cylinder for supplying fluid thereto under pressure to raise 50 the piston, a drain for the cylinder for releasing the pressure from the cylinder to lower the piston, and control valves for said intake and drain. 55

19. In a paper pulp machine, a supporting 60 frame including side washer posts and a transverse brace bar connecting the upper ends of the washer posts, a cylinder centrally carried by the transverse brace bar 65 of the supporting frame, a yoke member disposed adjacent the cylinder, a piston mounted in the cylinder and connected with the yoke member, means connecting the yoke member with the supporting shaft of a 70 washer, an intake for the cylinder for supplying fluid thereto under pressure to raise the piston, a drain for the cylinder for releasing the pressure from the cylinder to lower the piston, control valves for said intake and drain, and means for closing said 75 intake upon the movement of the yoke member to its upper limit of movement.

In testimony whereof, we affix our signatures.

EMIL A. PETERSON.
WILLIAM J. McGINNIS.
